FASTENER

Samuel W. Leming, Cincinnati, Ohio

Application October 12, 1943, Serial No. 505,991

4 Claims. (Cl. 24—243)

My invention relates to improvements in separable fasteners for use on hose supporters, the principal object in view being to provide a simply constructed, inexpensive fastener for the usual elastic bands of hose supporters, and which is especially designed for quick and easy attachment to the tops of stockings to distribute the pull throughout a substantial area of the tops so as to preclude the development of runs in stockings, frequently developing in the use of present day hose fasteners because the pull on the stockings is concentrated against a small area of the tops.

Other and subordinate objects are also comprehended by my invention, all of which, together with the precise nature of my improvements, will be readily understood when the succeeding description and claims are read with reference to the drawing accompanying and forming part of this specification.

In said drawing:

Figure 1 is a view partly in edge elevation and partly in longitudinal section illustrating my improved fastener, in its preferred embodiment, applied.

Figure 2 is a view in front elevation of the body member,

Figure 3 is a view in bottom plan of said body member,

Figure 4 is a view in perspective of the clamping unit,

Figure 5 is a view in transverse section taken on the line 5—5 of Figure 4,

Figure 6 is a view in transverse section taken on the line 6—6 of Figure 4, and

Figure 7 is a view in perspective of a modified form of clamping unit.

Referring to the drawing by numerals, my improved fastener, as illustrated, comprises, as its basic element, a skeleton body member 1 of suitable material and including a female clamping bar 2 adapted to extend across the thigh of the wearer of the supporter, and upwardly converging, bar-like sides 3 at the ends of the bar 2 connected at the upper ends thereof by a bar 4 around which the usual elastic 5 may be trained and buckled, as at 6, in loop form. The body member 1 is curved, as shown in Figure 3, to fit the thigh of the wearer. The bar 2 comprises a front, dovetailed channel 7, longitudinally concave, and extending from end to end thereof.

The channel 7 is designed to contain a male, sectional, clamping unit 8 comprising a pair of side-by-side, bar-like, flat sections 9, and a flat spreader section 10 also of bar-like form, said

sections being longitudinally curved in conformity with the curvature of the channel 7 and the outer sides of the sections 9 converging transversely so that the unit 8 is dovetailed in form to fit into the channel 7. The sections 9 are connected together at one end by a headed stud 11 on which said ends are slidable so that the sections may be moved toward or from each other laterally. At the other ends thereof, the sections 9 are connected together by a coil spring 12 extending through suitable apertures 13 in said sections, with its ends anchored in countersinks 14 in the outer sides of the sections by eye-screws 15 extending from said countersinks into the sections. The spreader section 10 has a reduced, parallel-sided end 16 pivoted between the sections 9 on the stud 11. The major portion of said section 10 is transversely wedge-shaped for a purpose presently apparent. The free end of the section 10 is provided with an edge notch 17 to straddle the spring 12, and a projecting lip 18 forming a finger grip.

Referring now to the use and operation of the described fastener, as will be clear, when the spreader section 10 is swung outwardly of the sections 9 of the unit 8, on the stud 11, said sections 9 will be drawn together by the spring 12 and the unit 8 thereby collapsed so that said unit may be entered in the channel 7. To secure the fastener to a stocking 19, the body member 1 is positioned on the inside of the top of the stocking, channel 7 outermost, and the collapsed unit 8 inserted in the channel 7 on the outer side of the stocking 19. A fold 20 of the stocking 18 will thus be entered in the groove 7. By swinging the spreader section in between the sections 9 of the unit 8, the sections 9 will be wedged or spread apart to clamp the fold 19 in the groove 7 against the sides of said groove. Thus, a portion of the stocking 18 equal to the length of the bar 2 and unit 8 will be secured to the member 1 and because of the length of the part thus secured, the pull on the stocking will be distributed throughout a wide area of the stocking so as to preclude the development of runs or tearing of the stocking top.

According to my invention, the member 1 may also be formed of a resilient plastic material, and a solid male clamping bar 19 may be provided, as shown in Figure 7, for fitting with a snap action between the upper and lower walls of the channel 7.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claims.

What I claim is:

1. A fastener for use on an elastic band of a hose supporter comprising a skeleton body member for attachment to said band including a bar having a longitudinal channel therein, and a clamping unit comprising a pair of laterally opposed bar-like sections adapted to be inserted in said channel and connected together for relative separation to clampingly engage the sides of said channel, and a spreader section interposed between said bar-like sections and constructed and arranged for operation to separate the bar-like sections.
2. A fastener for attaching a stocking top to a hose supporter band comprising a body member adapted to be attached to the band and including a bar having a longitudinal channel of dovetail form therein and forming a female clamping unit in which a fold of the stocking top may be inserted, a male clamping unit comprising a pair of laterally spaced bar-like sections adapted to fit in said channel and being slidably connected together for relative separation in said channel to clamp said fold against the sides of the channel, and a spreader section pivotally connected to said bar-like sections for swinging in between the same and being wedge-shaped in cross section to separate said bar-like sections by such swinging movement thereof.

3. A fastener for attaching a stocking top to a hose supporter band comprising a body member

adapted to be attached to the band and including a bar having a longitudinal channel of dovetail form therein and forming a female clamping unit in which a fold of the stocking top may be inserted, a male clamping unit comprising a pair of laterally spaced bar-like sections adapted to fit in said channel and being slidably connected together for relative separation in said channel to clamp said fold against the sides of the channel, and a spreader section pivotally connected to said bar-like sections for swinging in between the same and being wedge-shaped in cross section to separate said bar-like sections by such swinging movement thereof, said connection including a spring opposing relative separation of said bar-like sections.

4. A fastener for attaching a stocking top to a hose supporter band comprising a body member adapted to be attached to the band and including a bar having a longitudinal channel of dovetail form therein and forming a female clamping unit in which a fold of the stocking top may be inserted, a male clamping unit comprising a pair of laterally spaced bar-like sections adapted to fit in said channel and being slidably connected together for relative separation in said channel to clamp said fold against the sides of the channel, and a spreader section pivotally connected to said bar-like sections for swinging in between the same and being wedge-shaped in cross section to separate said bar-like sections by such swinging movement thereof, said male clamping unit being of dovetail form in cross section to facilitate clamping said fold against the sides of the channel.

SAMUEL W. LEMING.
